UNITED STATES PATENT OFFICE.

CLARENCE H. JORGENSEN AND PETER J. JORGENSEN, OF WAUPACA, WISCONSIN.

LUBRICANT CUP.

Application filed October 17, 1921. Serial No. 508,367.

To all whom it may concern:

Be it known that we, CLARENCE H. JORGENSEN and PETER J. JORGENSEN, citizens of the United States, residing at Waupaca, in the county of Waupaca and State of Wisconsin, have jointly invented certain new and useful Improvements in a Lubricant Cup, of which the following is a specification.

10 This invention relates to a cup to be mounted upon a machine element and adapted to confine a supply of lubricant and gradually deliver the same to a surface of the element requiring lubrication.

15 One object of the invention is to provide a lubricant cup that can contain an absorbent or wick-like filler and yet be filled promptly, at periods of replenishment, as for instance by applying a so-called oil gun 20 to the cup and forcing a full charge of lubricant therewith; and to this end an important feature of the invention consists in constructing the cup with a provisional chamber in addition to its wick-containing 25 reservoir so that in addition to the supply of oil that passes directly into the reservoir, an increment of lubricant will remain in the distributing chamber in quantity at least sufficient to respond to the full absorptive 30 capacity of the wick or even in excess thereof if desired; one feature incident to the preferred means for realizing this object of the invention consisting in forming the inner end of the provisional chamber, and 35 the partition between it and the reservoir, by a transverse diaphragm that is perforated to pass the lubricant therethrough; and another such incident feature consisting in utilizing this diaphragm to support the 40 wick in the wick reservoir.

Another object of the invention is to provide means whereby in the charging of the cup, a quantity of lubricant sufficient to flush the bearings, independently of the wick, and without taxing the reservoir supply therefor; and to this end another important feature of the invention consists in introducing, between the charging and discharging ports, 45 a direct delivery duct through which lubricant may flow directly to the bearing; one feature incident to the preferred means for realizing this object of the invention consisting in the extension of the direct delivery duct from the provisional chamber through 50 the reservoir to the discharge port of the

cup; another such incident feature consisting in mounting said direct delivery duct in and having it carried by the diaphragm; and still another such incident feature consisting in continuing the direct delivery flushing duct upward into, or, if desired, even through the provisional chamber, so that the provisional chamber will receive its quota of oil at the beginning of the 65 charging operation and the increment which it is to subsequently feed to the wick, will not be drained therefrom by said duct.

Another object of our invention is the provision of a lubricant cup in which the 70 flow of oil therefrom to the bearing is automatically controlled by a tube forming a conduit which extends from the bearing longitudinally of the discharge conduit of the oil cup and through which air is supplied to the oil cup and controlling the oil fed to the bearing.

In the accompanying drawing, in which the preferred embodiment of the invention is disclosed by way of illustration: 80

Figure 1 is a vertical axial section of the lubricant cup.

Figure 2 is a side elevation of the same.

Figure 3 is a detail view on an enlarged scale of the diaphragm, the direct delivery 85 duct mounted therein, and the wick supported thereby; and

Figure 4 is a section on the line 4*-4* of Figure 1.

1 represents the lubricant cup which may 90 be constructed of any conventional design and dimensions, but which, according to the present invention is equipped with a charging port 2 preferably having a gun-attaching neck 2^a, a discharge port 3, in the 95 threaded attaching end 4, and a transverse diaphragm 5 having flow-openings 6, and suitably sustained, as for instance, by ledge 7, in position to subdivide the internal space of the cup into a provisional chamber 8, 100 and a reservoir 9. Within the reservoir 9 is an absorbent 10, preferably in the form of strands of wick laced through openings 6 and thereby supported on the diaphragm 5, and trailing thence through the reservoir 105 and into the delivery port 2, beyond which it will preferably protrude a distance sufficient to wipe upon the surface to be lubricated. The wick 10 will largely fill the area of the flow openings 6 that are not 110 closed by the ledge 7, so that splashing of fluid lubricant upward from the reservoir

9 will be resisted, but lubricant can, nevertheless, pass from chamber 8 into and around the wick in reservoir 9, under the pressure of the gun.

- 5 The direct delivery duct is provided, preferably, by inserting a tube 11 centrally in the diaphragm 5 and having it extend downwardly through the reservoir to the discharge port so that on each occasion of replenishing the cup, lubricant will be conveyed directly to the bearing, to which the cup is applied, and thereby flush or prime the latter, independently of the supply through the wick, leaving to the wick the 10 more gradual supply to be effected by capillary action as the lubricant is consumed. Provisional duct 11 will preferably have an upward extension 11^a terminating above diaphragm 5 sufficiently to cause the trapping of a considerable body of oil in the provisional chamber, and prevent the same being drained out through the direct channel, but will not be permitted to obstruct delivery into the provisional chamber. 15 Preferably the action will be to first fill the provisional chamber and such space as may be available in the wick containing reservoir and then permit the direct delivery and flushing effect to result from the overflow. 20 The provisional chamber 8 lends itself advantageously, in operative principle, to the described organization of parts, in that, upon forcing lubricant, oil for instance, into the chamber 8, the oil may, at first, flow 25 into the duct 11, but flushing or priming of the bearing direct will follow the resistance resulting from filling the reservoir 9, around the wick therein, and largely the spaces among the fibers of the wick, then backing up into and filling the provisional chamber and leaving the latter an ample increment to supply any deficiency which develops as the process of wick absorption 30 proceeds.
- 35 It will also be further understood that the provisional tube 11 performs a further function of permitting entrance of air into the main reservoir, thus allowing the lubricant contained therein to pass into the reservoir 9 and from there through the wicking to the bearing. As long as there is a quantity of oil maintained around the end of the provisional tube 11 air is prevented from 40 entering the tube 11 but as soon as this oil is distributed throughout the bearing or is used, air is permitted to enter the tube 11 and an additional quantity of oil is supplied to the bearing. 45
- 50 Diaphragm 5 serves the further function of sustaining the closing spring 12 of a ball valve 13 with which the charging port is preferably equipped, and the extension 11^a serves to center said spring.

60 We claim:

- 65 1. A lubricant cup having a receiving

chamber and a discharging port, a reservoir below said receiving chamber, a diaphragm extending across the body of said cup and forming a division between said receiving chamber and said reservoir, an open ended 70 duct extending into said receiving chamber and to the end of said discharging port, and an absorbent extending into said discharge port and around said duct.

2. A lubricant cup having a receiving 75 chamber and a discharging port, a reservoir below said receiving chamber, a diaphragm extending across the body of said cup and forming a division between said receiving chamber and said reservoir, an open ended 80 duct extending into said receiving chamber and to the end of said discharging port, and an absorbent supported by said diaphragm and extending across said reservoir and into said discharge port whereby oil 85 is fed from said cup into a bearing.

3. A lubricant cup having a discharge port, a perforate transverse diaphragm subdividing the cup into a reservoir which feeds the discharge port and a provisional chamber which feeds the reservoir, a direct discharge duct supported by said diaphragm and delivering to said port and having its upper inlet end adjacent the top of the provisional chamber, 90 and an absorbent extending from the provisional chamber through the reservoir to and beyond the discharge port and beyond the discharge end of the duct.

4. A lubricant cup having a discharge 100 port, a perforate transverse diaphragm subdividing the cup into a reservoir which feeds said port and a provisional chamber which feeds said reservoir, a direct discharge duct supported by said diaphragm and extending above and below the latter, the duct portion 105 above the diaphragm being imperforate and having an open top substantially at the top of the provisional chamber, the lower end of the duct being adjacent the discharge port, and an absorbent extending from the provisional chamber through the reservoir to and beyond the discharge port and beyond the lower end of the duct.

5. A lubricant cup having a charging port at its upper end and a discharging port at its lower end, a perforate transverse diaphragm subdividing the cup into a reservoir which feeds the discharge port and a provisional chamber which feeds the reservoir, a direct discharge duct supported by said diaphragm, the upper portion of said duct extending above the diaphragm and terminating substantially at the top of the provisional chamber, the lower portion of the duct extending to the discharge port, an absorbent extending from the provisional chamber through the reservoir to and beyond the discharge port and beyond the lower end of the duct, a valve for closing 115 120 125 130

the charging port, and a valve spring bearing at one end against the valve and at its opposite end against the diaphragm, the lower portion of the spring embracing the upper portion of the duct which constitutes centering means for the spring.

6. A lubricant cup comprising a charging port, a provisional chamber, a perforate diaphragm forming a confine of said chamber, a reservoir beyond said diaphragm, a discharge port, a direct delivery duct extending from said chamber, through said diaphragm to said delivery port, and a wick in said reservoir, effecting a controlled delivery through said discharge port, and passing through the perforations of the dia-

7. A lubricant cup having storage and discharge chambers, the discharge chamber having a discharge port, a wick within the discharge chamber with one end extending through the discharge port and its opposite end within the storage chamber to feed lubricant to the discharge port, and a direct feed duct having its discharge end within the discharge chamber adjacent the discharge port and surrounded by a portion of the wick, the inlet end of the duct being within the upper portion of the storage chamber.

Signed at Waupaca, Wisconsin, this 7 day of Oct., 1921.

CLARENCE H. JORGENSEN.
PETER J. JORGENSEN.
